(57) **CLAIM**

The ornamental design for combination copier, scanner, printer, as shown and described.

DESCRIPTION

FIG. 1 is a perspective view of a combination copier, scanner, printer showing our new design;

FIG. 2 is a front view of the combination copier, scanner, printer;

FIG. 3 is a rear view of the combination copier, scanner, printer;

FIG. 4 is a right view of the combination copier, scanner, printer;

FIG. 5 is a left view of the combination copier, scanner, printer;

FIG. 6 is a plan view of the combination copier, scanner, printer; and,

FIG. 7 is a bottom view of the combination copier, scanner, printer.

The broken lines show portions of the design that form no part of the claim.

The single dotted broken line(s) define the bounds of the claimed design and form no part thereof.

1 Claim, 7 Drawing Sheets
